SIGNAL HORN

Roy D. Buell, Chicago, Ill.

Application December 29, 1945, Serial No. 638,203

2 Claims. (Cl. 116—142)

1

The present invention relates to a signal horn and more particularly to an alarm or signal horn for use on railway trains, ocean-going ships, buses, trucks, other motor vehicles, motor and sailboats, and other conveyances, also used as a signal for bridges, in factories and the like.

The signal horn of the present invention is one operated by high pressure air, of the type designed to give signals or alarms to avoid accidents under conditions where the usual type of horn would be inadequate. The lengths and diameters of the bells of the horns determine the tones, and the longer bells of larger diameter produce deeper and mellower notes of directional carrying power.

The present invention has to do with that type of signal horn or alarm wherein a vibratory unbalanced valve is utilized to produce the desired sound, and has for an important object the provision of a casing forming an air chamber certain walls of which support air outlet tubes in axial alignment and with the tubes arranged with their adjacent ends spaced apart sufficiently to receive an unbalanced vibratory valve disc between them, which disc vibrates to create sound in a horn connected to an air tube, when air under pressure is admitted to the interior of the casing, and with at least one of said walls movable with respect to the other wall to provide clearance for the valve disc when it is vibrated under high air pressure conditions.

Another object of the present invention is to provide an air pressure signal horn construction using an unbalanced vibratory disc valve to create sound, wherein the gap in which the valve vibrates may be varied in accordance with variable operating air pressures.

A further object of the present invention is to provide a casing forming an air chamber which casing has flexible wall means to provide clearance for an unbalanced valve for different operating pressures.

A still further object of the present invention is to provide a construction of signal horn having greater longevity under strenuous working conditions.

The above, other and further objects of the present invention will be apparent from the following description and accompanying drawing.

The invention is herein shown as applied to a two-way horn, although it is not thereto limited.

An embodiment of the present invention is illustrated in the accompanying drawing and the views thereof are as follows:

Figure 1 is a side elevational view of a two-way horn construction embodying the present invention;

Figure 2 is a fragmental enlarged axial sectional view through the arrangement of Figure 1;

Figure 3 is a transverse vertical sectional view

taken in the plane of line III—III of Figure 2; and

Figure 4 is a graph showing the relationship between air pressure and wall deflection for a given example.

The drawing will now be explained.

Figure 1 illustrates two horns, A and B, extending in opposite directions, horizontally, from a casing C which is provided with a base 5 whereby the horn structure may be mounted for use.

The horns A and B may be of any appropriate form and dimension to produce the character and tone of sound or note to be produced. In order that the produced note may be one of pleasing quality, and especially distinctive for signaling purposes, I prefer to utilize a form of horn similar to that of the ordinary slide trombone in which the musical tone is produced by the bell part of the horn.

The form of device chosen as an exemplification of the present invention includes a casing C which is formed as a casting, such as a die casting, preferably circular in vertical cross section, with the casing having a rigid apertured side wall 6 and a peripheral wall 7 from which an annular flange 8 extends. The other side of the casing is open. The central portion of the casing is preferably formed with a tubular boss, or sleeve, 9, with a portion of the sleeve lying inwardly of the inner surface of the wall 6, as at 10, and another portion of the sleeve lying outwardly of the outer surface of the wall 6, as at 11, although this construction is not essential, but is satisfactory. The casing C has a threaded opening 12, in a lower portion thereof, to receive the threaded end of a pipe 13 which is connected to the base 5.

If desired, the base 5, the pipe 13 and the casing 6 could be made as an integral casting. The base 5 is provided with suitable holes (not shown) for receiving screws or bolts for securing the structure in place on a suitable support.

The boss or sleeve 9 is formed to receive an air outlet tube or the like. In the present instance, the tubular portion of the horn B is shown as inserted in the sleeve 9, with its inner end projecting inwardly, slightly, of the inner end of the portion 10 of the sleeve, as may be observed in Figure 2. The horn B is suitably secured in the sleeve 9 so as to remain in connected relation regardless of the strenuous conditions of operation of the means to which the horn may be applied.

Closing the open side of the casing 6 is a flexible or yieldable wall, such as a diaphragm 14 which has its marginal portion secured to the flange 8 of the casing by suitable fastening means, such as screws 15. The center of the diaphragm 14 is apertured to receive an air outlet tube, the outlet tube in the present instance being a portion of the horn A. The horn A is secured to the diaphragm 14, in permanent relationship, as by

soldering at 16, or in any other suitable manner. The horn A is mounted in the diaphragm 14 in axial alignment with the horn B and arranged so that the inner end of the horn will be spaced a slight distance from the inner end of the horn B to provide a gap to receive therein an unbalanced valve 17, and provide sufficient space to enable vibration of the valve between the adjacent ends of the horns or air outlets. The valve 17 is in the form of a disk, which may be made of metal, a plastic or other suitable material.

In order to support the disc valve 17 in vibratory position between the adjacent ends of the horns or air outlets, and to mount it for free movement between these ends, under the influence of air pressure, means are provided, supported, as for example, by the portion 10 of the sleeve of boss structure 9, for loosely confining and supporting the peripheral portions of the disc valve. The supporting structure is slightly greater in diameter than the diameter of the disc valve so that the valve may freely vibrate without restraint other than restraint against displacement from between the adjacent ends of the horns.

The illustrated form of retaining means for the disc valve 17 comprises a cage formed by a plurality of pins 18 projecting from the portion 10 of the boss 9, into the chamber of the casing surrounding the space or gap between the adjacent ends of the horns, for receiving the disc valve 17 and holding it in place between the ends of the horns. The pins 18, forming the cage, are shown as four in number, arranged in equidistant circumferentially spaced relation about the axis of the casing. It is to be understood that the disc valve 17 might be retained in position between the adjacent ends of the horns, by at least three of such pins, but to reduce friction to a minimum, more than three are preferably utilized. It is to be understood that more than three such pins may be used, and it is also to be understood that the cage may be formed in a manner otherwise than by the pins, the main requirement being that it loosely confine the peripheral portion of the disc valve without undue friction.

When the horn structure is mounted for use, the pipe 13 is connected to a source of compressed air, such for example as an air compressor, or a tank containing compressed air. Installed in such connection is a suitable valve for controlling admission of compressed air to the interior of the casing 6 for operating the horn.

Air pressure utilized in signal horns of the character herein disclosed is sometimes as high as 200 to 250 pounds per square inch. Under certain conditions the pressure might be higher.

It will be understood that when compressed air is admitted to the interior of the casing 6, the disc valve 17 will be vibrated, producing the tonal sounds for which the horns are designed. It is possible, by proper design and dimension of the horns, to produce deep and mellow tones of great carrying power. The period of vibration of the disc valve 17 is controlled by the tonal frequency of the horn bell.

Horns of the character herein mentioned have been used and are being used on ships, high speed railway trains, such as some of the streamliners, on motor trucks and buses and other conveyances operating under conditions requiring the giving of audible warning signals, far in advance of the movement of the particular conveyance, and for signal purposes in factories and the like.

The vibration of the disc valve 17 is attained due to the aspirator effect created at the openings

into the horns A and B within the chamber C. As previously mentioned air is admitted to the chamber C under pressure and escapes from the chamber through the adjacent end openings of the tubes A and B. The disc 17 is floatingly disposed between the adjacent tube ends by the pins 18. When air escapes under pressure through an opening, it escapes at a velocity directly proportional to the pressure of the air within the confining chamber. When fluids pass over a surface at a high velocity, as when air under pressure escapes through a small opening, a low pressure area is created about the opening. Unsecured bodies are attracted toward the low pressure area, and if their size permits they will follow the stream of fluids through the opening.

Thus, it is here apparent that if air under pressure escapes through one of these openings, the valve disc 17 is attracted toward the low pressure area surrounding that opening until the valve 17 closes the opening. Thereafter, the air must escape through the opening of the opposed tube, switching the low pressure area and causing the valve 17 to move toward the other tube opening.

The rate of switching and vibration of the valve 17 is directly proportional to the air pressure within the chamber and to the rate of escape of the air. Initial vibration of the valve 17 is created when air is escaping from both the tubes A and B, because it is not possible for the valve 17 to be equi-spaced between the opposed adjacent tube openings, so as to be equally attracted toward both.

It is necessary that the disc valve be very freely vibratable and supported in a manner to reduce friction to a minimum. The herein described method of supporting the valve gives very satisfactory results in horn operation.

The signal horn will operate over a wide pressure range, from a few ounces of pressure to several hundred pounds, the greater the pressure the greater the increase in tone volume or loudness.

The provision of the flexible or yieldable wall 45 or diaphragm 14, as one of the walls for the air chamber within the casing 6, enables slight outward movement of the wall under high air pressure conditions to increase the gap between the tube ends to enable the valve disc to function properly, by slightly increasing the capacity of the casing chamber. The full line representation of the diaphragm in Figure 2 is the position it occupies when the pressure is low, and the dotted line position is another position assumed by the diaphragm when the pressure is elevated. It is to be understood that movement of the central portion of the diaphragm 14, to dotted line position of Figure 2, will move the inner end of the horn tube A a slight distance away from the adjacent end of the horn tube B thus providing additional clearance for the disc valve when it is vibrated under high air pressure conditions.

Figure 4 is a graph illustrating the relationship between air pressure in a casing such as casing C and the amount of flexible wall or diaphragm deflection of a bronze diaphragm 4" in diameter and having a thickness of .032".

The ordinate represents air pressure in pounds per square inch and the abscissa the diaphragm deflection in inches.

It will be noted, therefrom, that the deflection of the gap, due to air pressure variation, will be such as to permit vibration of the disc valve to produce pleasing, audible sound.

It is to be understood that a diaphragm of

different thickness would have a different amount of deflection.

It is within the purview of this invention to construct a casing having both the tube supporting walls flexible or yieldable, in which event the diameter of the casing would be reduced below that necessary when only one wall is flexible or yieldable.

Instead of two horns as illustrated, either horn A or B may be omitted and a short open-ended tube substituted in place of the omitted horn. The principle is the same with a single horn, but in that case the warning sound emitted is largely sent in one direction instead of in opposite directions.

The word "diaphragm" is herein used to designate any thin curtain or partition which may vibrate. That is to say, the term "diaphragm" is used to refer to a thin sheet of material, generally circular and restrained by having its periphery clamped but otherwise free to vibrate under the action of some driving force.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. A fluid pressure actuated signal horn construction capable of producing audible signals throughout a wide range of pressure which may vary from a few ounces to substantially over 200 pounds per square inch and including air chamber means of variable capacity which automatically adjusts itself to the fluid pressure delivered to it, comprising a box having one open side, a flexible membrane closing said open box side and capable of movement with respect to the plane of said open side to vary the volumetric capacity of said chamber within certain limits, said movement being dependent solely upon fluid pressure variations within said box, two air out-

let tubes projecting into said chamber and having their inner ends adjacent but spaced apart, one of said tubes passing through and immovably fastened to said membrane to move with it toward and away from the other of said tubes as the membrane is flexed by pressure differentials in said chamber, the other of said tubes passing through a portion of said box in axial alignment with said one tube and immovably fastened to said box portion, a vibratory valve disk supported between the adjacent ends of said tubes to alternately open said tubes to pressure, and said box having a pressure inlet.

2. A fluid pressure actuated horn comprising a casing with an apertured side and an opposed open side, a relatively stiff resilient diaphragm closing said open side and having an aperture aligned with the aperture in said apertured side, a vibratory valve in said casing between said apertures and arranged to alternately open and close said apertures, a fluid inlet for said casing, and said diaphragm being arranged to move away from the apertured side of the casing as fluid pressures in the casing increase and to return toward said apertured side responsive only to a decrease in said fluid pressure whereby said valve will have an operating space between the apertures which varies directly with variations in said fluid pressures.
